UNITED STATES PATENT OFFICE.

FREDERIC W. SLACK, OF CLEVELAND, OHIO, ASSIGNOR TO PEERLESS MOTOR CAR CORPORATION, OF CLEVELAND, OHIO, A CORPORATION OF VIRGINIA.

DESIGN FOR A RADIATOR SHELL.

Application filed July 5, 1928. Serial No. 27,388. Term of patent 3½ years.

To all whom it may concern:

Be it known that I, FREDERIC W. SLACK, a citizen of the United States, residing at Cleveland, in the county of Cuyahoga and State of Ohio, have invented a new, original, and ornamental Design for a Radiator Shell, of which the following is a specification, reference being had to the accompanying drawing, forming a part thereof.

Fig. 1 is a front view and Fig. 2 is a side view of the radiator shell showing my new design.

I claim:

The ornamental design for a radiator shell, as shown.

FREDERIC W. SLACK.
